HOLDER FOR SIGNALS AND THE LIKE

Thomas B. Owens, Cleveland, Ohio

Application March 20, 1947, Serial No. 736,048

5 Claims. (Cl. 248—163)

1

The invention relates to holders in the nature of supports, and particularly to a holder for danger signals such as lanterns and pots serving as warnings or caution lights at the site of road installations, repairs, and maintenance, and similar building and repair operations.

It is well known that lanterns and pots utilized for the above-mentioned purposes are frequently knocked over and rendered useless for the stated purpose, and are often stolen. A frequent and expensive consequent of the resultant lack of warning to users of thoroughfares where the danger signal should be in service is the defense of claims against those alleged to be at fault made by those who claim to be damaged by reason of the lack of warning lights. Incidental but important further disadvantages of such warning lights as are now constructed and placed in roadways are that they are positioned too low to best serve their purpose, and cannot be securely positioned, or positioned in places where their secured position would be assured and where they would serve their best purpose without considerable chance of being displaced.

The instant invention is designed to largely obviate the above-mentioned disadvantages and, consequently, provide means for holding a danger signal whereby it will adequately serve the purpose for which it was intended and at the same time assure the security of the signal itself.

The principle of the invention is described and illustrated herein by an embodiment thereof in a holder for lanterns.

The annexed drawings and the following description set forth in detail certain means illustrating the improvements in holders for signals and the like, the same, however, showing only one form in which the principle of the invention may be embodied.

In said annexed drawings:

Figure 1 is a top plan view of the improved holder, the supporting legs therefor being shown in full lines in one position when supporting the holder in service, and, in dot-and-dash lines, in another selective position, the suggestion of a lantern positioned in the holder being also shown in dot-and-dash lines;

Figure 2 is a side elevation of the several elements shown in Figure 1;

Figure 3 is a vertical longitudinal section, taken in the planes indicated by the line 3—3, Figure 1; and

Figure 4 is a vertical transverse section, taken in the plane indicated by the line 4—4, Figure 1, there being shown in this figure in dot-and-dash

2

lines a still further selective position of one of the supporting legs for the holder, such position being substantially midway between the relatively right angular positions indicated by the full line and dot-and-dash showings of the supporting legs in Figures 1, 2, and 3.

Referring to the annexed drawings in which the same parts are shown by the same respective numbers in the several views, the improved holder 10 is formed from the following parts: A sheet metal blank bent up into an open-sided bed-like frame whose major portion is a platform 1, two depending opposed side rails 12 secured between the respective ends of the bent-up sheet member 1, a pair of opposed depending legs 16 adjustably and pivotally mounted in the ends of the bent-up sheet member 1, a pair of washers 21 mounted on horizontal portions 20 of the depending legs 16 and serving with bent-down portions of the platform 1 to form abutments for a pair of compression springs 22 serving slidably to tend to hold the supporting legs 16 in their innermost positions, relatively manually adjustable lantern clamping bodies 23 and 28 having clamping fingers 27 and 30, and a tension spring 25 controlling the spacing between the clamping fingers 27 and 30.

The detail of construction, assembly, and functioning of the several elements thus generally above-mentioned is as follows:

A sheet metal blank is bent to form relatively right angular and downwardly-extended flanges 2 adjacent its ends and then sharply bent to form longer and substantially parallel upwardly-extended flanges 3 of its extreme ends, the portion of the blank between the ends 2—3 forming a platform serving as the top 1 of the improved lantern holder.

Before the blank is thus bent it is stamped out 40 to form aligned circular apertures 8 in the respective flanges 2—3 somewhat above the bottom of the latter and substantially midway of their length, rectangular holes 10 in the flange 3 adjacent the top of the latter and vertically aligned with the apertures 8, rectangular holes 9 in the respective flanges 2—3 and horizontally aligned with the apertures 8 substantially midway the apertures 8 and one end of the flanges 2—3, and rectangular inclined holes 11 in the flange 3 substantially midway the holes 9 and 10. The sheet metal blank is also stamped to form a transverse slot 6 extending from one side of the top 1 to a plane somewhat spaced from the plane of the opposite side, an opposed pair of transverse cuts 7 being also formed adjacent one side of the top

and communicating with the slot 6, the material from these cuts 7 being bent downwardly and inwardly to form a pair of ears 7¹ whose purpose will be hereinafter described. The top 1 is also cut to form a pair of longitudinally-aligned square holes 5, somewhat spaced from the flanges 2—3, and the material therefrom is bent downwardly to form a pair of ears 5¹ whose purpose also will be hereinafter fully described.

To complete an upside down box-like formation of the top 1 and its flanges 2 and 3, depending side members 12 are provided which have inwardly bent end flanges 13 spot welded, as indicated by 14, to the inside faces of the flanges 2. One of these side members 12 is notched at its top edge, as indicated by 12¹, for a purpose hereinafter fully described.

The lantern 15 is supported upon the top 1 of the upside-down box-like formation between spring clamping fingers 27 and 30, there being a pair of these fingers on each side upwardly projected from body members 23 and 28, respectively, the body member 23 being manually adjustable relatively to the body member 28 which is fixed, so that the clamps may serve for lanterns of different sizes.

The fixed clamping body member 28 is a longitudinally extending strip spot-welded, as indicated by 28¹, to the top 1 substantially centrally of one side edge of the latter and adjacent said edge and is formed with outwardly-extended horizontal divergent portions 29 from which are upwardly projected the fingers 30 having hook-like clamping upper ends 30¹.

The body 23 of the adjustable clamp is formed with an inwardly-extended part 23¹ formed with an open-ended recess 23² within which, and between the legs 28 formed thereby, is secured to the part 23¹ one end of a compression spring 25, the other end of the spring 25 being secured to the top 1, the spring 25 intersecting the cross slot 6 formed in the top 1. The body 23—23¹ slides in the notch 12¹ and between the ears 7¹ and the bottom surface of the top 1. It is thus seen that the adjustable clamp body 23 may be pulled outwardly against the tension of the spring 25 to regulate the distance between the respective clamping fingers 27 and 30 for the reception and holding of lanterns 15 of different sizes, this functioning of the adjustable clamp 23 being manually effected by means of a finger piece 26 formed from and upwardly projecting from the adjustable clamp body 23.

Lanterns 15 are usually formed with bottom outwardly-extended peripheral beads 15¹, and to accommodate these beads 15¹ and insure the secure holding of the lantern 15, the respective clamp fingers 27 and 30 are formed adjacent their bottom ends with outwardly-extended beads 32 forming grooves 31 within which the lantern beads 15¹ may be accommodated.

The holder with its lantern mounted thereon is supported at a distance above the ground or from any other base engageable by the supporting end portions of a plurality of legs 16 which are so formed and can be so connected with the end flanges 2—3 of the top 1 that they serve their purpose either when positioned vertically or horizontally or midway between these relatively right angular positions. To this end, the major portion of these supports consists of a bottom end substantial length 16 constituting the base-engaging end portion, the support being formed adjacent its top with a variedly bent structure as follows. First, one end portion of this upper part

of the leg is bent outwardly to form a finger piece 17, substantially semi-circular in outline, and then bent sharply inwardly and outwardly to form a closely knit doubled formation or projection 18 which engages the upper central hole 10 in the end flange 3, full lines in the figures, the leg material then being bent downwardly to form a short vertical portion 19 located adjacently exteriorly of the flange 3, the leg material then being bent into a relatively right angular end piece 20 which is slideable through the aperture 8 in the end flanges 2 and 3 and then through the ear 5¹ depending from the top 1. A washer 21 is secured to the leg part 20 adjacent its inner end, and between this washer 21 and the depending ear 5¹ the compression spring 22 is mounted around the leg portion 20.

As shown for purposes of illustration in the accompanying drawings, there are two of the legs 16 and they are of like formation and assembly and function, and are formed with pointed lower ends 16¹ for easy application to a surface in which they may be mounted.

Oftentimes, it may not be found preferable or even suitable to mount the lantern 15 with the legs 16 in a vertical position, so that provision is made for mounting the legs horizontally or in a position between horizontal and vertical positions. This is provided for by means of the rectangular hole 9 formed through the end flanges 2 and 3, and the intermediate hole 11 formed through the end flange 3, which hole accommodates the doubled formation or projection 18 of the leg 16 similarly to the accommodation thereof by the top hole 10. The adjustment is effected, of course, by pulling the upper part of the leg out of and away from the end flanges 2—3, thus releasing the doubled leg formation 18, turning the box-like formation upon the leg portion 20 and positioning the leg formation 18 in that flange hole giving the desired angular relation between the top 1 and the axis of the base-engaging leg portion 16.

Sharpened lower ends 16¹ are shown upon the legs 16 for the purpose of mounting them upon or in a surface such as dirt, but the conditions incident to road building and other operations for which the lantern holder serves are often such that the holder cannot conveniently be mounted in dirt. In that case the holder can be maintained in position by mounting the lower ends of the legs below any weight therefor, or between any elements that will serve to maintain them in position, such as piled brick, stone, or timber thereon, or pushing them through barricades, or any other method of holding them rigid so that they may extend outwardly in a suitable direction for supporting the lantern on the top 1 where it will without undue chance of being knocked over or stolen serve as an efficient danger signal.

In addition to the improved holder serving efficiently as a support for a danger signal, and with a minimum chance of its being disturbed by traffic, it is evident that the holder and signal cannot be stolen by merely opening an automobile door and reaching out and taking them, but such stealing would usually require getting out of the automobile and removing the signal from the holder or pulling the holder out of the ground or away from its mounting. These last-mentioned operations would require considerable time and probably necessarily be effected outside of the automobile which render the chances of detection quite great and no doubt would obviate

most of the attempts at stealing. The holder does not interfere with the operation and maintenance of the lantern, such as lighting it, adjusting its light, or refueling it.

What I claim is:

1. A holder for signals and the like having a flat body portion formed with exterior upwardly-extended end flanges and adjacently interior comparatively shallow and substantially parallel flanges, opposed side members extending between and secured to the flanges to form an upside down box-like formation, an annular series of at least three spaced holes formed through the flanges at each end of the body, an aperture formed through each flange about which the series of holes is grouped, supporting legs each having a base-engaging end portion, an opposite end portion resiliently and pivotally mounted on and beneath the flat body, biased inwardly thereof, and passed through the aperture, and an intermediate portion formed with an exterior finger piece and having a doubled-over part for selective engagement with the flange holes, and means mounted on the flat body for resiliently clamping a signal on the top thereof.

2. A holder for signals and the like having a main body, signal-retaining means supported thereby, a supporting leg having a base-engaging end portion and an opposite end portion upon which the body is pivotally mounted, the body being formed with an aperture through which the body-mounting portion of the leg slidably passes, the body having a series of spaced holes grouped about the aperture as a center, and the supporting leg being bent intermediate its ends to form a projection passable through any selected hole, the construction being such that, upon sliding the mounting portion of the leg through the aperture sufficiently to release the projection from the body hole through which it is passed, the body can be turned upon its pivotal axis for registration of the projection with another body hole, thus providing various angu-

lar supported positions for the body relative to the axis of the leg.

3. A holder for signals and the like, characterized as in claim 2, in which the leg is spring-mounted and biased to hold the projection normally interiorly of a body hole.

4. A holder for signals and the like, characterized as in claim 2, in which supporting legs are provided upon opposed sides of the body, and in which the latter is formed with an aperture and a series of holes grouped thereabout for each leg.

5. A holder for signals and the like having a flat body portion formed with end flanges, opposed side members extending between and secured to the flanges to form a box-like formation, an annular series of at least three spaced holes formed through each end flange, an aperture in each flange about which the series of holes is grouped, supporting legs each having a main base-engaging end portion, an opposite end portion resiliently and pivotally mounted on the flat body, biased inwardly thereof, and passed through the flange aperture, and an intermediate portion having a doubled-over part for selective engagement with the flange holes, and signal-retaining means for mounting a signal on the top of the flat body.
